UNITED STATES PATENT OFFICE

2,155,727

ELECTRIC SWITCH

Martin J. Madison, Philadelphia, Pa.

Application April 11, 1938, Serial No. 201,434

4 Claims. (Cl. 200—36)

The object of the invention is to provide improvements in switches broadly, but more particularly in a type of switch which is adapted for use, either within or upon any well known form of mechanical alarm clock, electrical clock, or other device, of such construction and operation as is capable of actuating the said switch.

Another object is to provide a switch, which in the case of an alarm clock can be attached to the alarm winding shaft, whether said shaft carries a left or right hand screw thread, and either to switch on or off an electric current, and thereby energize or de-energize extraneous apparatus, such for instance as opening or closing windows, turning on or off lights, starting a fuel burner, turning on or off air-conditioning apparatus, or a wide list of additional operations, which would otherwise require manual attention.

A further object is to provide a switch of this character with suitable means to support its weight upon the same or other support than that upon which the clock (or other actuating mechanism) is supported, and also to prevent said switch from revolving with respect to the said clock, when suddenly actuated by the mechanism of the latter.

Still another object is to provide a device of this character, with means to adjust the height of said switch-supporting means, to accommodate clock and similar mechanisms of various heights, that is, various heights of the alarm winding shaft with respect to the supporting surface upon which the clock or equivalent actuating mechanism rests.

And a still further object is to provide a device of this type, which is of the simplest possible construction and operation, thereby making it possible to construct the same inexpensively and with a high degree of efficiency.

With the objects thus briefly stated, the invention comprises further details of construction and operation, which are hereinafter fully brought out in the accompanying drawing, in which Fig. 1 is a rear elevational view of a clock and attached switch of the improved design and illustrating one embodiment of the invention; Fig. 2 is a side elevation of the same; Fig. 3 is an enlarged rear elevational view of the switch per se shown partly in section and with the rear closure plate removed; Fig. 4 is a section on the line 4—4 of Fig. 3; Fig. 5 is an enlarged diametrical section taken through the rotatable contact-supporting disc; and Fig. 6 is an enlarged perspective view of the pair of spaced contacts carried by the oscillatory arm and also shown in Figs. 3 and 4.

Referring to the drawing, any well known type of alarm clock 1 is shown as being provided with the usual knob 2 for manually setting the position of the hands of the clock, together with the

usual wing nut 3 and connected shaft for winding the clock mechanism and the knob 4 and attached pointer, for respectively manually setting and indicating the time when the alarm is intended to operate. The clock is also provided with the usual alarm winding shaft 5, from which the usual wing nut has been removed in this instance. The clock itself is, furthermore, provided with suitable feet 6 for operatively supporting it in upright position upon a surface 7. However, it is to be understood that the improved switch mechanism hereinafter described, while shown in the drawing as attached to the winding shaft 5 and positioned upon the outside of the clock as a whole, may instead be employed within the clock casing and form a unitary part of the clock mechanism.

One embodiment of the invention is here shown as comprising a hollow casing 8 of whatever shape and size may be desired and comprising a normally forward wall 9, through which projects an auxiliary shaft 10 having a threaded axially positioned bore 11, adapted to be normally attached to the winding shaft or stem 5, as indicated in Figs. 1, 2 and 4. This auxiliary shaft 10 upon its inner end portion, that is, within the casing 8, is provided with an annular shoulder 12, which is surrounded by a corresponding annular portion 13 of a member, formed of insulating material and comprising an integral arm 14, which extends radially outwardly through an elongated slot in the upper portion of the casing 8, and in which slot said arm is adapted to be manually oscillated between the full-line and the dot-and-dash line positions shown in Figs. 1 and 3. To an intermediate portion of said arm, there is secured within the casing 8 the fixed ends of a pair of spaced, substantially parallel, resilient contact members 14a and 14b.

Beyond the arm 14 within said casing, the shaft 10 is provided with an annular flange 15 and adjacent thereto with an annular shoulder 16, upon which is frictionally mounted a preferably circular disc 17, carrying at one point of its periphery a transversely extending metallic member 18, and at a substantially diametrically opposite point said disc being provided with a cut-out region 19, bounded by oppositely positioned shoulders 20, between which extends a pin 21, or other suitable stop, carried by the forward wall 9 of said casing, and operative to limit the amplitude of oscillation of the disc 17. Upon rotation of said disc, the member 18 is shifted to a position between and connecting, or away from engagement with the said contact members 14a and 14b.

Said disc is secured with the proper degree of friction upon the shaft 10 by means of a washer 22 and nut 23, the rearmost portion of said shaft being threaded to receive a suitable wing nut 24.

and extending rotatably through a plate 25, forming a closure for the rear and otherwise open side of said casing 8. While the weight of the improved switch is not great, and might in certain sizes be satisfactorily supported by the winding shaft 5, it is preferable to provide a separate support for said switch and especially is it necessary to provide means for preventing said switch casing from rotating unrestrained upon the rotation of said winding shaft. For this purpose any suitable depending means may be provided for contacting with one of said clock-supporting feet 6, or directly with the supporting surface 7. However, for purposes of illustration, there is here shown a U-shaped member comprising a support-engageable base 26 and a pair of laterally spaced upwardly projecting arms 27, which extend slidably along the laterally opposite side walls 28 of said casing, and are adjustably secured thereto by set screws or other suitable means 29.

In the operation of this device, the auxiliary shaft 10 is secured to the alarm winding shaft 5, by either right or left handed adapter, and whether the threads connecting the two are of the right or left-hand type, the operation of the device is the same and the shaft 5 can be wound by manual engagement with the wing nut 24, while the disc 17 is restrained beyond a certain point from further rotation by engagement of the pin 21 with one of said shoulders 20. In the drawings it is assumed that the alarm mechanism is wound by a clockwise motion of the shaft 10, and in Figs. 3 and 4 the arm 14 is set, so that rotation of the disc 17 upon operation of the alarm mechanism will cause an electrical connection between the spaced contacts 14a and 14b, which are carried by the arm 14, and have their free end portions extending upon the opposite sides of and in slidable contact with the surfaces of the disc 17 and are, consequently, electrically connected when the contact 18 is shifted by the alarm mechanism into a position between them. On the other hand, and by contrast, if the electrical device whose operation is controlled by said switch is normally operating, then the arm 14 is initially placed in the dot-and-dash position shown in Fig. 3, so that the contact members 14a and 14b are electrically connected by the disc-contact 18, until operation of the alarm mechanism at a predetermined time, as indicated by the indicator 4, shifts said disc so as to withdraw said disc contact from between said contact members, thereby breaking the circuit and discontinuing the operation of the particular electrical device controlled by said switch. If the alarm mechanism is such that it is wound by a counterclockwise rotation of the switch shaft 10 and wing nut 24, the relative movements of the disc 17 and arm 14 will be merely the reverse of that hereinbefore described.

In considering the scope of the present invention, it is to be understood that references to clocks and clock mechanisms generally are intended to include any and all mechanisms capable of actuating a switch of the type herein described, and that the alarm winding shaft of a clock merely represents any shaft or the like such as will operate the said switch. Furthermore, it is quite obvious that many changes can be made in minor details of the structure, as well as in its

operation, without departing from the principles involved.

Having thus described my invention, what I claim as new and desire to protect by Letters Patent of the United States is:

1. The combination of a clock mechanism having an alarm winding shaft adapted to rotate at a predetermined time, with a switch mechanism comprising a shaft member detachably connected to said alarm shaft and through which said alarm shaft can be reversely rotated to wind the alarm mechanism, a disc frictionally carried by said shaft member and in turn carrying a metallic contact, and an oscillatory arm provided with a pair of metallic brush contacts, adapted in one position of said arm and a given position of said disc to be electrically connected by said disc contact, and movement of said shaft member being operative to shift said disc contact from between said brush contacts. 20

2. The combination of a clock mechanism having an alarm winding shaft adapted to rotate at a predetermined time, with a switch mechanism comprising a shaft member detachably connected to said alarm shaft and through which said alarm shaft can be reversely rotated to wind the alarm mechanism, a disc frictionally carried by said shaft member and in turn carrying a metallic contact, and an oscillatory arm provided with a pair of metallic brush contacts, adapted in one 25 position of said arm and a given position of said disc to be electrically connected by said disc contact, and movement of said shaft member being operative to shift said disc contact from between said brush contacts, and means to support the 30 weight of said switch mechanism independently of its connection with said winding shaft. 35

3. The combination of a clock mechanism having an alarm winding shaft adapted to rotate at a predetermined time, with a switch mechanism comprising a shaft member detachably connected to said alarm shaft and through which said alarm shaft can be reversely rotated to wind the alarm mechanism, a disc frictionally carried by said shaft member and in turn carrying a 40 metallic contact, and an oscillatory arm provided with another metallic contact, said last-mentioned contact being adapted for engagement with said disc contact when said arm and disc are in predetermined relative positions, and said 45 contacts becoming separated upon the movement of either said arm or said disc into a different angular position. 50

4. The combination of a clock mechanism having an alarm winding shaft adapted to rotate at a predetermined time, with a switch mechanism comprising a shaft member detachably connected to said alarm shaft and through which said alarm shaft can be reversely rotated to wind the alarm mechanism, a disc frictionally carried 60 by said shaft member and in turn carrying a metallic contact, and an oscillatory arm provided with another metallic contact, said last-mentioned contact being out of engagement with said disc contact when said arm and disc are in predetermined relative positions, and said contacts 65 becoming inter-engaged upon the angular movement of either said arm or said disc into a different angular position. 70
